UNITED STATES PATENT OFFICE.

WILLIAM B. ARNOLD, OF ABINGTON, MASSACHUSETTS.

DESIGN FOR A HEEL END.

SPECIFICATION forming part of Design No. 31,567, dated September 26, 1899.

Application filed July 31, 1899. Serial No. 725,695. Term of patent 14 years.

To all whom it may concern:

Be it known that I, WILLIAM B. ARNOLD, a citizen of the United States, residing at North Abington, in the county of Plymouth and Commonwealth of Massachusetts, have invented and produced a new and original Design for a Heel End, of which the following is a specification, reference being had to the accompanying drawings, forming part thereof.

In the drawings, Figure 1 is a plan view of the heel end, showing my new design. Fig. 2 is a front end elevation thereof, and Fig. 3 is a side elevation.

As shown in the drawings, the leading or material feature of my design for a heel end consists of a plane portion a , having a smooth curved outer edge a' and having an interior made up of a plurality of points a^2 , separated

from each other by indentations a^3 , excepting at the extreme rear end, where the points a^2 are substantially in contact with each other. The forward ends have a beveled or ogee cut, as shown at a^4 , Fig. 3.

Having described the nature of my design, what I claim as new, and desire to secure by Letters Patent, is—

The design for a heel end, as herein shown and described.

In testimony whereof I have signed my name to this specification in the presence of two subscribing witnesses.

WILLIAM B. ARNOLD.

Witnesses:

GEO. H. MAXWELL,
HOMER A. ARNOLD.
